CLOTHESLINE MECHANISM

George R. Davies, East Hartford, Conn.

Application June 4, 1935, Serial No. 24,791

19 Claims. (Cl. 68—3)

This invention relates to clothes line mechanism and more particularly to improvements in such mechanism wherein the entire length of the line may be utilized for supporting clothes.

Previous to this invention most endless or so-called pulley lines permitted the use of approximately only one-half the length of the line. In instances where the use of the entire length of the line was contemplated, various disadvantages were encountered, among which was the objectionable inconvenience of the attaching means or clothes pins interfering with the pulleys, the clothes becoming tangled with those on the adjacent portion of the line and the lack, in such devices, of efficient line tightening and guiding means, of efficient clothes hanging devices and, when desired, of a selectively operative clothes releasing means.

The principal object of this invention is to provide an improved clothes line mechanism whereby the above objectionable features will be overcome.

Another object is to provide a clothes line mechanism whereby the entire length of line may be utilized for supporting clothes in an efficient manner.

Another object is to provide in such mechanism efficiently operative means to guide the line about the pulleys, which means will permit the line to be disposed about the area over which it is hung in any convenient arrangement.

Still another object is to provide, as part of such mechanism, a simple, efficient and inexpensive line tightening means.

A further object is to provide, as part of such mechanism, means to selectively release clothes from the line or to release them consecutively and to do this substantially automatically.

A still further object is the provision of a clothes line mechanism which is comparatively simple and sturdy in structure, efficient in operation and inexpensive to make and to maintain in operation.

To these and other ends the invention consists in the novel features, parts and combinations thereof hereinafter illustrated, described and claimed.

In the accompanying drawings:

Fig. 1 is a general plan view of a clothes line mechanism embodying the features of this invention;

Fig. 2 is a plan view of one of the pulleys with associated parts of the mechanism shown in Fig. 1;

Fig. 3 is a side view of the pulley and associated parts shown in Fig. 2;

Fig. 4 is a side view of another pulley;

Fig. 5 is a bottom plan view of parts shown in Fig. 2;

Fig. 6 is a section on line 6—6 of Fig. 2, and showing the operation of certain parts;

Fig. 7 is a section similar to Fig. 6, but showing another operation of certain parts; and

Fig. 8 is a detail of a part.

The clothes line mechanism illustrated in the drawings and embodying the features of this invention herein generally comprises a plurality of line receiving and guiding pulleys 10, 11 and 12 about which a clothes line 13 runs. The pulleys 15 10 11 and 12 are herein shown secured to widely spaced apart supports 14 and 15 respectively, by means of swingable hooked bars 16 that engage the pulleys in an eye 17 formed on a pulley holder or casing 18, to which the pulley is rotatably supported on studs 19. Each pulley holder 18 consists of a body portion 21 that extends over one end face of the pulley and a flange portion 22 that depends from portion 21 and about a portion of the periphery of the pulley to prevent the line running out of the groove 23 formed therein and for a purpose to be hereinafter disclosed. Preferably only substantially one quarter of the periphery of the pulley is covered by the flange 22 and the eye 17 is formed therein substantially midway between its ends.

The pulley 10 is pivotally supported to a holder or casing 24 by a pin 25, the holder 24 having a body portion 26 extending over one of the end faces of the pulley and a flange 27 depending from the body portion and about a portion of the periphery of the pulley to cover the groove 28 formed therein. The pulley 10 is also provided with a circumferentially disposed flange 29 which in this instance is an extension of one of the edges of pulley 10, depending therefrom for a purpose to be hereinafter disclosed. A hollow boss 30 is formed on the upper surface of the body portion 26, of pulley holder 24, in which a toothed bar 31 is disposed and through the opening 32, thereof, the bar may slide. The bar 31 is provided with a closed eye end 33 enclosing the eye portion 34 formed on a plate 35, adapted to be secured to a supporting member.

A catch finger 36 is pivotally secured to the boss 30 between ears 37 formed at one end thereof. The finger 36 is provided with a hooked end 38 adapted for catching in the teeth of bar 31 to releasably prevent relative movement between the bar and the pulley 10 in one direction. The

finger is normally urged by gravity into tooth engaging position, since in normal use the pulley is disposed to rotate in a horizontal plane. Relative movement between the bar 31 and pulley 5 may be caused by pulling on a handle 39 affixed to a cable or other flexible member 41 running over a pulley 42 secured to a supporting member, by plate 43. The cable 41 is secured to an eye 44, formed on holder 24 and disposed substantially 10 midway between the ends of flange 27, by means of a connector 45. By means of the toothed bar 31, finger 36 and cable 41 the line 13 may be tightened in an expeditious and convenient manner to maintain the same taut and insure its 15 proper disposition in, and operation with, the pulleys 10, 11 and 12.

Clothes supporting members herein comprising, a well known type of spring operated clothes clamping or gripping members 51, in combination 20 with a line engaging and clothes clamping member or hanger 52, are provided. The body portion 53 of hanger 52 may be permanently secured to one of the arms 54 and 55 of the member 51, in this instance arm 54, by rivets 56. Side flanges 57 are provided on the hanger 52 extending from the body portion 53 thereof alongside of the arms 54 and 55 of member 51 to insure against misalignment thereof and to support the same when they are pressed together, to open the 30 clothes gripping jaws 58 thereof against the tension of operating spring 59. The upper end of body portion 53 is turned over away from the body portion to form a loop 61 which extends outwardly away therefrom and through which the line 13 is threaded and is free to slide. The disposition of the loop 61 extending outwardly away from body portion 53 at one side and the side flanges 57 being extended from the other, permits the free movement of these hangers 52 about 35 the pulleys when on the line 13 and supporting clothes therefrom the loop 61 fitting the grooves in the pulleys and the body portions readily passing through the space between the periphery of the pulleys and the flanges of the casings thereof as shown in Figures 6 and 7.

The clothes line mechanism of this invention also includes clothes clamping member opening means, herein illustrated as an arcuately shaped member 71 having a pair of ears 72 and 73 projecting upwardly therefrom and embracing the shank portion 74 of the eye 44, formed on casing 24 of pulley 10, and being pivoted thereto by a pivot pin 75. The member 71 extends about the peripheral flange 29 of pulley 10 and has its arcuate form disposed thereabout slightly eccentric thereto in a horizontal plane as clearly shown in Fig. 5. The member 71, in this instance, is disposed below the bottom edge of flange 27 of casing 24 so as not to be interfered with thereby in its pivotal movements about pin 75.

The pivot pin 75 is disposed in respect to ears 72 and 73 so as to support member 71 eccentrically whereby it will normally hang substantially vertically with its walls vertically parallel to the flange 29. The inner edges of the ears 72 and 73 are adapted to engage flange 27 of casing 24 to prevent swinging of member 71 beyond their vertical position away from flange 29, but to allow it to readily swing toward flange 29. The end 77 65 of member 71, due to the eccentric disposition of the latter in respect to flange 29, is spaced therefrom an amount to permit it to enter between arms 54 and 55 of the clothes clamping member 51 as shown in Fig. 2 when the latter is moved 70 toward the same by movement of line 13 in the

direction of arrow 81 in Fig. 1. Continued movement of line 13 in this direction slides arm 55 along the outer surface of member 71, swinging the latter about its pivot 75 as shown in Fig. 7 and permitting the passage of the clothes clamping members 51 and the clothes held thereby past pulley 10. During this operation, the body portion 53 of hanger 52, due to its position between flanges 27 and 29 retains the members 51 against swinging, maintaining them substantially vertically disposed.

The end 78 of member 71 due also to the eccentric mounting of the latter in respect to flange 29 is spaced horizontally therefrom an amount to insure the entering of arm 55 between the member 71 and flange 29, as shown in Fig. 2 when the line 13 is moved about pulley 10 in the direction of arrow 82 in Fig. 1. In as much as member 71 is prevented from swinging away from flange 29 by the engagement of inner edges of ears 72 and 20 13 with the flange 27, the arm 55 of clothes clamping members 51 is pressed toward arm 54 as shown in Fig. 6 to open jaws 58 thereof, thereby automatically releasing any clothes held thereby. The cooperation of flange 29 whereby the body portion 53 of hanger 52 is prevented from swinging, insures positive opening of jaws 58 during this operation. While flange 29 is herein shown extending from pulley 10, arrangement of the parts is possible whereby the periphery of pulley 10 below the line groove could be used for this purpose.

By the provision of the above described combination of features, a complete clothes line mechanism is provided which is particularly efficient in use, comparatively simple in structure and which possesses all of the advantages and objects contemplated. The several features of the complete clothes line mechanism, above described, further cooperate to permit the selective removal of any supported article from the line without disturbing the others, by the movement of the line in one direction and to automatically release all of the clothes one at a time when the line is moved in the other direction.

The cooperation of the flanges 22 and 27, the peripheries of the pulleys and the body portion 53 of hangers 52, insures that the clothes clamping members 51 and the clothes supported thereby, will hang vertically and not twist about the line while it runs over the respective pulleys. Other features assisting in the obtainment of advantageous results, are the side flanges 57 on hanger 52 for supporting the arms of clothes clamp 51, the line tightening means, the provision of supporting the hangers 52 loose upon the line insuring the vertical hanging of the clothes and the disposition of the entire loop portion 61 of these hangers to ride in the pulley groove, whereby the body portion 53 thereof is free to travel by the pulley periphery disposed substantially in a vertical plane. Applicant's clothes line mechanism as above described is especially useful in permitting a plurality of pulleys to be used in order to dispose the several lengths about and around various upstanding members in the user's yard, such as trees, poles etc.

While there has been illustrated and described herein, a preferred embodiment of this invention, it is to be understood that the same is not to be limited thereto in all of its details, as many variations and modifications are possible that may lie within the spirit of the invention and scope of the appended claims.

What I claim is:—

1. In a clothes line mechanism, the combination of an endless clothes line, a substantially horizontally disposed pulley, a holder for said pulley and to which the latter is pivotally secured, a portion of said holder extending over one end face of said pulley and having a hollow boss extending radially with respect to said pulley and formed on the upper surface thereof, a toothed bar having one end secured to a support on which said boss is slidably mounted, a catch swingably mounted on said boss and adapted to selectively catch in each notch of said bar, and a cable having one end secured to said holder and adapted at its other end to be manually actuated to quickly move said pulley relatively to said bar to cause the pulley to slide along said bar and said catch to engage the desired notch in said bar.

2. In a clothes line mechanism, the combination of an endless clothes line, a substantially horizontally disposed pulley, a holder for said pulley and to which the latter is pivotally secured, a portion of said holder extending over one end face of said pulley and having a hollow boss extending radially with respect to said pulley and formed on the upper surface thereof, a toothed bar having one end secured to a support on which said boss is slidably mounted, a catch swingably mounted on said boss and adapted to selectively catch in each notch of said bar, and a cable secured to said pulley holder, reeved about a pulley secured to a support and depending substantially vertically therefrom for engagement and manipulation by a downward pull thereon to quickly move said pulley relatively to said bar to cause the pulley to slide along said bar and said catch to engage the desired notch in said bar.

3. In a clothes line mechanism, the combination of an endless clothes line, a substantially horizontally disposed pulley, a holder for said pulley and to which the latter is pivotally secured, a portion of said holder extending over one end face of said pulley and having a hollow boss extending radially with respect to said pulley and formed on the upper surface thereof, a flange depending downwardly from the said pulley, a toothed bar having one end secured to a support on which said boss is slidably mounted, a catch swingably mounted on said boss and adapted to selectively catch in each notch of said bar, and a cable secured to said pulley holder substantially midway between the ends of said depending flange, said cable being reeved about a pulley secured to a support and depending substantially vertically therefrom for engagement and manipulation by a downward pull thereon to quickly move said pulley relatively to said bar to cause the pulley to slide along said bar and said catch to engage the desired notch in said bar.

4. In a clothes line mechanism, an endless line, pulleys for supporting said line, releasable means to hold clothes upon said line, and means to automatically engage said holding means and actuate it to release clothes from said clothes holding means when said line is moved longitudinally in one direction and to engage said clothes holding means to prevent the release of the clothes when said line is moved in the other direction.

5. In a clothes line mechanism, an endless line, pulleys to support said line, clothes gripping means on said line, said clothes gripping means being openable to release said clothes, and means associated with one of said pulleys to engage and actuate said clothes gripping means to release the clothes held thereby when the line is moved longitudinally in one direction and to pre-

vent such release when the line is moved in the other direction.

6. In combination, an endless line, a pulley about which said line is reeved, an article gripping member mounted on said line, and means cooperating with the peripheral edge of said pulley to actuate said article gripping means to release an article held thereby.

7. In combination, an endless line, a pulley about which said line is reeved, an article gripping member mounted on said line, and means cooperating with the peripheral edge of said pulley and adapted to engage it to actuate said article gripping means to release an article held thereby, when said line is moved about said pulley in one direction, said means being operable to engage said article gripping means to prevent release of articles from said member when said line is moved about said pulley in the other direction.

8. In combination, an endless line, a pulley about which said line is reeved, an article gripping member mounted on said line, an arcuate member disposed adjacent the periphery of said pulley with the curvature thereof eccentric to the curvature of the periphery of said pulley, and means on said article gripping member engageable by said arcuate member to release articles held thereby.

9. In combination, an endless line, a pulley about which said line is reeved, an article gripping member mounted on said line, an arcuate member disposed adjacent the periphery of said pulley with the curvature thereof eccentric to the curvature of the periphery of said pulley, and means on said article gripping member engageable by said arcuate member to selectively release the article therefrom or to prevent such release, as said member is passed thereby on its movement with said line about said pulley.

10. In combination, an endless line, a pulley about which said line is reeved, an article gripping member mounted on said line, an arcuate member disposed adjacent the periphery of said pulley with the curvature thereof eccentric to the curvature of the periphery of said pulley, said arcuate member being swingable toward and away from the periphery of said pulley and cooperating therewith and with said article gripping member when in one of its swung positions to cause release of articles held by said member.

11. In combination, an endless line, a pulley about which said line is reeved, a releasable article gripping member mounted on said line, an arcuate member disposed adjacent the periphery of said pulley with the curvature thereof eccentric to the curvature of the periphery of said pulley, said arcuate member being swingably mounted relatively to the periphery of said pulley and normally disposed with its adjacent surface substantially vertically parallel thereto for engagement with said article gripping member to actuate the same.

12. In combination, an endless line, a pulley about which said line is reeved, an article gripping member mounted on said line, an arcuate member disposed adjacent the periphery of said pulley with the curvature thereof eccentric to the curvature of the periphery of said pulley, said arcuate member being swingably mounted relatively to the periphery of said pulley and normally disposed with its adjacent surface substantially vertically parallel thereto, and means associated with said article gripping member to actuate the same and being engageable by said arcuate member, when the same is in normal posi-

tion, to actuate said article gripping member to release articles therefrom when said article gripping member is moved about said pulley with said line.

5 13. In combination, an endless line, a pulley about which said line is reeved, an article gripping member mounted on said line, an arcuate member disposed adjacent the periphery of said pulley with the curvature thereof eccentric to the curvature of the periphery of said pulley, said arcuate member being swingably mounted relatively to the periphery of said pulley and normally disposed with its adjacent surface substantially vertically parallel thereto, and means associated with said article gripping member engageably by said arcuate member, when the same is in normal position, to be actuated to release articles from said article gripping member when said article gripping member is moved about said pulley with said line in one direction and to engage said arcuate member and swing it out of normal position and thereby prevent actuation to release articles when said article gripping member is moved about said pulley with said line in the other direction.

10 14. In a clothes line mechanism, an endless line, a pulley about which said line is reeved, an article gripping device having normally closed jaws on said line, and means to actuate said article gripping device to open said jaws when said line is moved in one direction about said pulley to release articles therefrom, said means being inoperative when said line is moved about said pulley in the other direction.

15 15. In a clothes line mechanism, an endless line, a pulley about which said line is reeved, an article gripping device having normally closed jaws on said line, and common means to actuate said device to open said jaws when said line is moved in one direction about said pulley and to prevent actuation thereof when said line is moved about said pulley in the other direction.

20 16. In a clothes line mechanism, in combination, an endless line, a pulley about which said line is reeved, an article gripping device on said line including, a pair of fingers hinged together intermediate their ends to present article gripping members and pressable members to open

said gripping members, means to press together said pressable members to open said gripping members when said device is moved about said pulley, and means confining the sides of said fingers to prevent relative sidewise movement thereof when acted upon by said pressing means.

25 17. In a clothes line mechanism, in combination an endless line, grooved pulleys about which said line is reeved, one of said pulleys having a flange disposed circumferentially thereabout in opposed position to the groove therein, an article gripping device on said line including, a pair of openable, normally closed fingers, a member secured to one of said fingers and adapted to extend between said pulley and said flange to prevent said device from swinging while passing by said pulley, means, adjacent another pulley, to actuate said fingers to release an article held thereby, said member, of said article gripping device, having a portion extending over each side of said fingers to prevent sidewise relative movement thereof, while being actuated by said means.

30 18. In a clothes line mechanism, in combination, an endless line, a pulley about which said line is reeved, a flange disposed circumferentially about said pulley, an article gripping device including, a pair of arms movable toward each other to release an article, and a member having a portion secured to and extending from one of said arms to connect with said line, and adapted to pass between said pulley and said flange when moved about said pulley with said line, and having another portion substantially U shaped in cross section straddling the sides of said fingers to restrain sidewise movement thereof.

35 19. In a clothes line mechanism, in combination, a clothes line, an article gripping device on said line including, a pair of members hinged together to provide article engaging jaws and arms for actuating said jaws to release an article therefrom, and means to engage said arms when they are passed thereby, by movement with said line in one direction, to cause actuation of said jaws to release an article and to engage said arms when passed thereby in another direction to prevent actuation of said jaws.

GEORGE R. DAVIES.
